(57) **CLAIM**

The ornamental design for a portable computing device with low profile hinge, as shown and described.

DESCRIPTION

FIG. 1 is a perspective view of a portable computing device with low profile hinge in an open configuration;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is an enlarged perspective view of a portion of the hinge thereof as indicated in FIG. 1;

FIG. 9 is a perspective view thereof in a closed configuration;

FIG. 10 is a front view thereof;

FIG. 11 is a back view thereof;

FIG. 12 is a side view thereof;

FIG. 13 is another side view thereof;

FIG. 14 is a top view thereof;

FIG. 15 is a bottom view thereof; and,

FIG. 16 is an enlarged perspective view of a portion of the hinge thereof as indicated in FIG. 9.

Broken lines shown in the drawings illustrate portions of the portable computing device and form no part of the claimed design.
